UNITED STATES PATENT OFFICE.

GEORGE T. ROSENGREN, OF CHICAGO, ILLINOIS, ASSIGNOR TO ENTERPRISE TOOL AND METAL WORKS, OF CHICAGO, ILLINOIS, A CORPORATION OF ILLINOIS.

SAD-IRON.

1,142,984.

Specification of Letters Patent. Patented June 15, 1915.

Application filed February 20, 1915. Serial No. 9,483.

To all whom it may concern:

Be it known that I, GEORGE T. ROSENGREN, a resident of Chicago, in the county of Cook and State of Illinois, have invented certain new and useful Improvements in Sad-Irons, of which the following is a full, clear, and exact description.

The invention relates to sad irons, and more particularly to that class of sad irons which comprise a burner for liquid fuel, such as kerosene or gasolene.

In practice, it has been found that some sad irons provided with kerosene burners did not operate satisfactorily because efficient provision was not made for thoroughly vaporizing the liquid-fuel before its delivery into the burner tube, which resulted in insufficient vaporization and preheating, and at times the liquid would be discharged from the generating tube.

One object of the invention is to provide an efficient device whereby kerosene, as well as gasolene, will be effectively preheated and vaporized for combustion in the burner-tube, and this object is attained by surrounding the vaporizing tube with a jacket of high conductivity, such as copper, which will distribute the heat to all portions of the vaporizing tube and thoroughly heat it to effect vaporization of the liquid therein, the tube being formed of a harder metal, such as brass, which will not scale from the heat and thus cause a deposit or obstruction in the generator.

When kerosene is used as a fuel, the nozzle of the generator is provided with a very minute opening which occasionally, and sometimes frequently becomes clogged. In the devices heretofore used, the interruption of the fuel, caused by insertion of a cleaning needle, usually disposed on the end of the valve for controlling the supply of liquid fuel, would cause the generator to cool so rapidly that preheating of the generator was necessary every time that the nozzle was cleaned.

Another object of the present invention is to provide a sad iron with an improved generator which will remain sufficiently hot for effective vaporization and for a sufficient period to permit the cleaning needle to be operated through the nozzle without necessitating preheating of the generator after each cleaning operation.

The invention further designs to provide

an improved sad iron adapted for liquid fuel.

The invention consists in the several novel features hereinafter set forth and more particularly defined by claims at the conclusion hereof.

In the drawings: Figure 1 is a perspective of a sad iron, embodying the invention. Fig. 2 is a perspective of the generator and burner. Fig. 3 is an enlarged section of the generator and burner.

The sad iron comprises a body 10 and a cover 11 which is removably connected thereto in any suitable manner. The body 10 is hollow and comprises a bottom 12, side 14 having openings 15 therein and a rear wall 16. A handle 17 is secured to the upper member of a resilient U-shaped strip or bar 18 which has its lower member 19 secured to the cover 11. A strip of insulation 20 is interposed between the cover and member 19 to prevent heat conduction to the handle.

The improved sad iron is particularly adapted to be heated by liquid fuel and a reservoir 21 is provided for containing the fuel. The reservoir 21 may be of usual construction, and is adapted to hold the liquid under pressure. Member 19 of the resilient connection between the handle and the cover is extended rearwardly and laterally to form a supporting-arm 22 for the reservoir. The latter is secured to a forwardly turned terminal 23 on the rear end of arm 22. The reservoir is secured to terminal 23 by a nut 24 and a reversely curved pipe 25 leading from the bottom of the reservoir extends through an elongated slot 26 formed in a member 22. This supporting-arm and its terminal 23 form a somewhat yielding or resilient support so that the reservoir 21, if it strikes an obstruction, as sometimes occurs in use, will not be broken, the yielding support serving to cushion any blow against the reservoir. Pipe 25 conducts the liquid fuel to an upwardly extending nipple 27 of a valve-casing 28, to which it is connected by a suitable union coupling 29. Nipple 27 extends through a slot 30 at the rear end of cover 11, and casing 28, of which the nipple 27 is a part, is secured to the cover by a nut 31, co-operating with a shoulder 32 to clamp the casing on the cover.

A generator-tube 33 has one of its ends screw-threaded to the casing 28. A valve-seat 34 for a valve 35 which controls the

supply of liquid to the generator is formed in casing 28. Valve 35 is on the inner end of a stem 36 which is screw-threaded to a nipple 37 of casing 28 and is provided with 5 a wheel 38 at its rear end whereby the valve may be manipulated.

In sad-irons, it is particularly desirable to make effective provision against leakage of the liquid-fuel, particularly if kerosene is 10 used, and for this purpose, a double packing is provided around valve-stem 36. One packing 39 is held in a gland 40 which is screw-threaded to nipple 37 and an additional packing 41 is held in the outer end of 15 the gland 40 by a follower 42 which is screw-threaded into the outer end of the gland. By adjusting the gland 40, the packing 39 may be tightened and by adjusting the nut 42, the packing 41 may be tightened 20 around the stem 36. This packing-means is simple in construction and provides effectively against leakage of the liquid around the valve stem 36.

The generator-tube 33 is disposed beneath 25 the cover 11 and in the body of the sad iron. A nozzle 44 is screwed into the discharge end of this tube and this nozzle is formed with a very small opening 45 through which the vapor passes to a mixer-pipe 46, which 30 is secured in the cover by a screw 47. The cover 11 is depressed or recessed, as at 48, so that sufficient air from the outside for combustion will pass into and be mixed with the vapor in pipe 46. Pipe 46 connects with 35 the burner-pipe 49 which is provided with cross-slits 50 of gradually increasing length, to discharge the vaporized fuel at the point of consumption adjacent the base 12 of the iron. The rear end of burner pipe 49 is 40 closed by a plug 49^a. The mixer and burner-pipe are formed of a U-shaped tube. A sub-burner 51 is secured to the rear end of burner-pipe 49 to heat the generator. This sub-burner 51 comprises a nipple 52 which 45 is secured in the burner 49 and its top wall is provided with small holes 53 and a longitudinal slit 54 which are disposed below the generator to provide a flame under the generator, which will thoroughly heat it to 50 cause vaporization of the liquid fuel. In practice, it has been found that when the burner 51 is provided with a longitudinal slit and these holes, the flame will burn evenly and regularly, so that the generator 55 will be constantly kept at a high temperature for effective generation.

The ends of the mixer 46 and the nozzle 44 are correlative disposed to effect a proper mixture of air and vapor when either 60 kerosene or gasoline is used. In practice, it has been found to be desirable to provide a sad iron that may be used with either of these fuels.

The generator-tube 33 is usually formed 65 of brass and a tubular copper jacket 60 sur-

rounds said tube. This jacket is driven on to said tube to provide a snug fit and close contact between the tube and the jacket. This copper jacket is heated to a high degree by heat from the burner 51 and, by 70 reason of its high conductivity, it conducts and distributes the heat to all portions of the generator tube 33 to which the liquid fuel is delivered. In practice, it has been found that when this copper jacket is used 75 around a brass generator tube, the latter will be kept so hot that the fuel will not condense on the needle 61 in the tube.

Generator tube 33 is provided with a hexagonal portion 62 whereby it may be turned 80 into the casing 28 and at the rear end of jacket 60 the diameter of the generator tube 33 is reduced, as at 63, to prevent excessive conduction of heat from the generator tube rearwardly, or to prevent the generator 85 from being cooled by conduction from the exposed casing and rear end of tube 33 to that portion of the generator tube and the jacket where they are subjected to heat from the burner 51.

A groove 40^a is formed in the packing gland 40 to minimize conduction between the two portions of the glands in which the packings are held.

Needle 61 is provided with a point 65 95 which is adapted to enter the small jet-hole 45 in the nozzle 44. This point is adapted to clean out hole 45 whenever it becomes clogged, as is frequently necessary when kerosene is used for fuel. This point can 100 be operated to clean out said hole by turning the wheel 38 quickly, to force the point through the hole and then turning said wheel to withdraw the point from the nozzle. In practice, it has been found that 105 when the generator is constructed as described, it will be heated to such a high degree that kerosene will not condense on the needle during the cleaning operation, and so that when the point is operated 110 quickly, the hole 45 can be cleaned out without necessitating preheating of the generator before the burner will operate. In starting the use of the iron, after it has become cold, it is necessary to use a torch to preheat the 115 generator.

A pin 70 extends across the bent portion of the U-shaped pipe forming the mixer and burner. This pin serves to interrupt the flow of gas so that its pressure will not cause it to pass the first of the series of slits 50 without issuing therefrom.

The invention thus provides an improved sad iron which is particularly adapted for 125 and has been found to be successful in the use of kerosene as a fuel and which may also be used for gasoline. The generator is constructed so that it will thoroughly heat and vaporize liquid fuel, particularly kerosene. Provision is made for keeping the generator 130

hot so that there will be no difficulty in keeping the iron constantly heated. The use of a flat U-shaped strip for supporting the reservoir simplifies the construction of the device and provides a yielding support which avoids breakage of the reservoir. The sub-burner for the generator is particularly adapted to provide a small regular flame for heating the generator.

10 The invention is not to be understood as restricted to the details set forth, since these may be modified within the scope of the appended claims, without departing from the spirit and scope of the invention.

15 Having thus described the invention, what I claim as new and desire to secure by Letters Patent, is:

1. In a sad iron, the combination of a body, a handle, a reservoir for liquid fuel, 20 a burner for heating said body, and a generator tube connected to said reservoir and provided with a surrounding jacket of high heat conductivity.

2. In a sad iron, the combination of a body, a handle, a reservoir for liquid fuel, a burner for heating said body, and a generator tube connected to said reservoir and provided with a surrounding jacket of high heat conductivity, and a burner for heating 30 said jacket.

3. In a sad iron, the combination of a body, a handle, a reservoir for liquid fuel, a burner and a valve and casing connected to said reservoir, a generator-tube having 35 one of its ends secured in said casing, said tube being provided with a reduced portion for lessening heat-conduction between its end which is connected to said casing and the remaining portion thereof.

40 4. In a sad iron, the combination of a body, a handle, a reservoir for liquid fuel, a burner pipe, and a generator tube con-

nected to said reservoir and provided with a jacket of high heat conductivity, said tube being provided with a reduced portion exteriorly of said jacket for lessening heat-conduction between the different portions of 45 said tube.

5. In a sad iron, the combination of a body, a handle, a reservoir for liquid fuel, 50 a burner for heating said body, a generator tube connected to said reservoir and a burner for heating said generator connected to the burner and having a longitudinal slit and holes therein for the escape of fuel toward 55 said tube.

6. In a sad iron, the combination of a body, a handle, a reservoir for liquid fuel, a burner for heating said body, a generator tube connected to said reservoir and provided with a jacket of high heat conductivity, and a burner for heating said generator connected to the burner, having a longitudinal slit and holes therein for the escape of fuel toward 60 said tube.

65 7. In a sad iron, the combination of a body, a cover for the body, a burner in the body, a generator, a handle secured to the said body, a U-shaped bar secured to said cover and extended rearwardly and laterally 70 from the cover to form a support and a reservoir secured to said support.

8. In a sad iron, the combination of a body, a cover for the body, a burner in the body, a generator, a handle secured to the 75 said body, a reservoir, a bar secured to said cover and having one of its ends bent to form a U-shaped support, and a reservoir secured to said support.
